UNITED STATES PATENT OFFICE.

CHARLES H. BOMBARDIE, OF SOUTH BEND, INDIANA, ASSIGNOR TO WIREBOUNDS
PATENTS COMPANY, OF KITTERY, MAINE, A CORPORATION OF MAINE.

BOX.

1,329,333.

Specification of Letters Patent. Patented Jan. 27, 1920.

Application filed February 20, 1917. Serial No. 149,925.

To all whom it may concern:

Be it known that I, CHARLES H. BOMBARDIE, a citizen of the United States, and resident of South Bend, in the county of 5 St. Joseph and State of Indiana, have invented an Improvement in Boxes, of which the following description, in connection with the accompanying drawings, is a specification, like characters on the drawings representing like parts.

This invention relates to boxes and more particularly to that form of box commonly known as a crate wherein the sides are made of spaced slats. The purpose of my 15 invention is to provide a substantial box with a removable lid which may be utilized either as an open-top receptacle or as closed shipping container and which may be easily brought into box form and closed and re- 20 opened repeatedly without the use of special apparatus and without impairing the strength of the box itself.

My invention will be best understood by reference to the following description of one 25 illustrative embodiment thereof taken in connection with the accompanying drawings, wherein:

Figure 1 is a perspective view of the box with the cover removed;

30 Fig. 2 is a perspective view of the box with the cover in place and fastened;

Fig. 3 is a perspective view of the blank from which the side and bottom sections of the box are made;

35 Fig. 4 is a view of one of the end sections;

Fig. 5 is a view of one of the lower corners of the box as seen from the outside; and

Fig. 6 is a view of one of the cover wires.

Referring to Fig. 3, the body of the box 40 herein shown is constructed from side and bottom sections 1, 3 and 5, embodying cleats 7, 9 and 11 respectively and suitable side material, here shown as spaced slats 13. The several sections are assembled with the 45 cleats in alinement and secured together in coöperative foldable relationship by suitable binding wires. I have here shown wires 15 secured by staples straddling the same and passing through the side material into the 50 cleats and other wires 17 secured to the side material and disposed between the cleats. As will be well understood by those familiar with the art, the three sections can be folded up in coöperative relationship with end sections 55 about to be described and the cleats

7 and 11 will mate with the cleats 9, forming a mortise and tenon joint therewith in the embodiment of the invention shown, and the wires 15 and 17 will encircle the box so made.

In the present example of the invention the slats 13 which are next to the lower edges of the box are spaced from the ends of the cleats, as clearly shown in Fig. 3, while the slats nearest the upper edges of the box are flush with the ends of the cleats for a purpose presently to be described. The spacing of the slats near the lower corners provides for an open corner of the 60 crate which is desirable as it will provide 65 for thorough ventilation of the contents. Since the sides of the box are constructed in this manner I secure the sections together in a somewhat closer proximity than would otherwise be necessary, so that the wires 15 70 will be tensioned over the angle formed by the mating cleats, as clearly shown in Fig. 5 and bite into the wood slightly at this place. By so constructing the crate a firm 75 product is provided for, whereas if the wires 80 15 were not tensioned over the cleats there would be an opportunity for lost motion 85 which would make the crate wobbly.

Suitable end sections 19, which may be 90 in the form disclosed in Fig. 4, are assembled 85 with the blank of Fig. 3. As shown in Fig. 4, the end section 19 may comprise a cleat 21 corresponding to the fourth side of the box and adapted to mate with the cleats 7 and 11 to frame the ends of the completed 95 box, suitable wall material 23, here in the form of spaced vertical slats, and means for securing the wall material in position at a location remote from the cleat 21. In the present embodiment of the invention, this 100 means takes the form of a second cleat or batten adapted to interlock with the cleats 7 and 11 of the side sections. For this purpose the cleat or batten 25 may be provided with suitable tenons and the mortises of the 105 cleats 7 and 11 may be made of such length as to receive both the tenons of the cleat 9 and those of the batten 25 (see Fig. 5). It will be apparent that the end sections 110 may be placed with the battens 25 on the cleats 9 and the side sections folded up to bring the parts into the form of an open-top or five faced box.

Referring to Fig. 4, it will be seen that in forming the end sections I utilize but

two vertical slats, spaced from each other and from the ends of the cleat 21 and batten 25. By this arrangement a substantial end is provided for the crate with the use of a minimum of material and thorough ventilation is assured.

Suitable means are provided to hold the parts of the box body in position and I have here disclosed separate wires 27 corresponding to the fourth side of the box and of sufficient length to reach between the ends of the wires 15. These wires 27 have provision whereby they may be detachably secured to the wires 15 to form continuous 10 bindings encircling the box ends as shown in Fig. 1 to hold all the parts together. While any suitable means may be provided for fastening together the wires 15 and 27, I have here disclosed them as having their 15 ends formed into coöperating portions of so-called "Tyloop" fastenings. These fastenings are formed by returning the end of the wire along the standing part and intertwisting it therewith to form a loop, as clearly 20 illustrated in Fig. 2. To secure together two wires the loop at the end of one is reeved through the loop at the end of the other and bent over to form a hook. The parts are so proportioned that the throat 25 or bent part of this hook consists of a double thickness of intertwined wire and not of two parallel lengths thereof. In other words, the wire which forms the hook is bent inwardly of the loop and not across the 30 loop. Much greater strength and durability is provided for in this manner. A fastening such as described may be readily engaged and disengaged without the use of a special 35 tool and without impairing the strength of 40 the wire.

I provide a cover 29 for use with the box described and I have here shown this cover as comprising suitable slats 31 adapted to extend along the length of the box and rest 45 on the cleats 21 and connected together and reinforced at the ends by the battens 33. The cover 29 may be provided with wires 35 corresponding to the wires 17 of the box body and adapted to be engaged therewith 50 to form box-encircling binding members when the cover is in position, as shown in Fig. 2. For this purpose the wires 35 and 17 may be provided with suitable coöperating 55 portions of tyloop fastenings.

When it is desired to fasten the cover on the box to form a closed shipping receptacle, the wires 27 are removed from the cleats 21 by releasing the fastenings binding them to wires 15, the cover is placed in position 60 and the wires 27 readjusted over the cover 29 and once more secured to the wires 15 so that continuous binding wires are provided, encircling the box body and cover and holding the latter firmly in place. The wires 35 and 17 may also be fastened together.

It will be recalled that in describing the side sections shown in Fig. 3, it was pointed out that the slats 13 nearest the upper corners of the box were flush with the ends of the cleats. By reference to Figs. 1 and 2, 70 it will be seen that the slats of the cover are also so positioned that they reach to the box corner and form an overlapping joint with the slats of the box body instead of providing a space along the edge of the box, 75 such as is formed at the lower edges. This is to provide a firm bearing for securing the wire bindings about the box when the tyloop fasteners or similar fastening devices are engaged with each other. These fastenings 80 are so tensioned that the wires will cut slightly into the meeting edges of the slats and bind the cover firmly in place.

It will be seen from the description above that I have provided a box and in particular a crate well adapted for the storage or shipment of fruit and the like, which is not only a strong shipping container when closed but a convenient and substantial storage receptacle when the cover is removed and stored away. Furthermore, the whole box may be conveniently shipped or stored in knock-down or shook form and readily assembled, either as an open-top receptacle or as a closed shipping receptacle 95 without the use of a special tool or the exercise of special skill. No metal fastenings in the nature of nails are utilized and the box may be assembled and disassembled and opened or closed an indefinite number of 100 times without in any way impairing its quality. The covers 29 are simple and can be compactly stored when the box is being used without a cover and do not embody any loose parts likely to be lost.

It will be recognized that the box as a closed shipping receptacle illustrated in Fig. 2 preserves practically unimpaired the advantage of boxes of the wirebound type wherein a structure composed of light side 110 material and reinforcing cleats is supported against the shocks of use by universally flexible binding wires combined with the side material and cleats and tensioned about the same. Under diagonal strain tending to 115 disrupt the box the wires will assume a somewhat diagonal position constricting about the same and resisting distortion. When the box is used without the cover, it will still have encircling bindings around the ends 120 and will therefore depend on the tensile strength of the wire rather than on the strength of the wooden slats and cleats for resistance to breakage. It will be noted that the upper cleat 21 is secured in position by 125 the binding and forms a handle by which the box can be lifted and carried for short distances.

Having thus described in detail one illustrative embodiment of the invention, what 130

I claim and desire to secure by Letters Patent is:

1. A wirebound box comprising cleats outlining the ends of the box; side material for three sides of the box; the cleats corresponding to the fourth side being unattached to side material; a separate lid; and wire bindings extending around the cleats at the ends of the box; the portions of said bindings corresponding to the fourth side being separable and adapted for joinder with the remainder of said bindings either to secure the parts in open-top box form or to secure the lid. 45
- 15 2. A wirebound box having separable end sections and a separable lid, the body of the box comprising relatively foldable side and bottom sections connected by wire-bindings, and a common fastening means for securing the side and end sections together in open-top box form or for securing the lid. 50
- 20 3. A wirebound box comprising relatively foldable side and bottom sections connected by wire bindings; end sections embraced thereby; and wires separable *per se* uniting said wire bindings across the top of the box and adapted to hold the parts together with or without a lid. 55
- 25 4. A wirebound box comprising relatively foldable side and bottom sections connected by wire bindings; end sections embraced thereby; a separable lid for the box; and means for use with or without the lid to hold the parts in box form. 60
- 30 5. A wirebound box comprising relatively foldable side and bottom sections connected by wire bindings; end sections embraced thereby; a separate lid for the box; and detachable means for use with or without the lid to hold the parts in box form. 65
- 35 6. A box comprising side and bottom sections each embodying side material and cleats, binding wires secured to the ends of said sections and between the ends thereof and holding together the sections in co-operative foldable relationship, end sections arranged to interlock with the cleats aforesaid and having cleats corresponding to the fourth side of the box, a cover adapted to rest on said last mentioned cleats said cover carrying a wire or wires corresponding to the intermediate binding wire or wires of the side and bottom sections and having provision for detachable engagement with the same, and separate wires adapted to co-operate with the binding wires at the ends of the side and bottom sections having provision for detachable joinder therewith to form continuous box-encircling bindings with or without the cover in place. 70
- 40 7. A box comprising side and bottom sections each embodying side material and cleats, binding wires secured to said cleats and holding the sections together in co-operative foldable relationship, end sections arranged to interlock with the cleats aforesaid and having cleats corresponding to the fourth side of the box, a cover adapted to rest on the latter cleats, and separate lengths of wire corresponding to the fourth or cover side of the box having provision for detachable joinder with the binding wires aforesaid to form continuous bindings encircling the box with or without the cover in place. 75
- 45 8. A box comprising body sections secured together in co-operative foldable relationship by binding wires, end sections adapted to interlock with said body sections, a separate cover, and wires separate from the body, end sections and cover having provision for joinder with the wires of the body to form continuous bindings encircling the box with or without the cover in place. 80
- 50 In testimony whereof I have signed my name to this specification,
- CHARLES H. BOMBARDIE. 85
